UNITED STATES PATENT OFFICE.

EMORY J. BENEDICT, OF ST. LOUIS, MISSOURI.

SANITARY DISPENSING-RECEPTACLE.

1,195,902.

Specification of Letters Patent. Patented Aug. 22, 1916.

Application filed November 2, 1915. Serial No. 59,186.

To all whom it may concern:

Be it known that I, EMORY J. BENEDICT, a citizen of the United States, residing at St. Louis, in the State of Missouri, have invented certain new and useful Improvements in Sanitary Dispensing-Receptacles, of which the following is a specification.

My present invention relates to an improved sanitary dispensing receptacle, one object of the invention being the provision of a jar like receptacle, having a large mouth and a removable cap or cover, which in turn is provided with a gravity actuated closure, thus providing a receptacle especially adapted for dispensing sugar, syrup and the like for household, restaurant, lunch room and hotel use.

A further object of the present invention is the provision of a sanitary dispensing receptacle that is provided with a novel form of removable cap, which in turn is provided with a gravity actuated closure, that makes the receptacle dust, fly and insect proof, thus producing a very useful and practical article.

In the accompanying drawings: Figure 1 is a side elevation of the receptacle the mouth end being in section, and the cap also being in section with its closure in the position it assumes when the receptacle is in an upright position. Fig. 2 is a top plan view of the cap. Fig. 3 is a sectional view illustrating the closure in the open position.

Referring to the drawings, the numeral 5 designates the receptacle, here shown as a glass jar, but it is to be understood that it may be made of any material that will be sanitary, and permit of it being readily washed, such receptacle being provided with 30 the wide exteriorly threaded mouth 6, of usual construction. The cap 7 is made somewhat similar to a jar cap, and fits over the mouth 6 with a gasket 8 interposed to provide a tight joint. By this means the 45 cap may be removed at will to permit of the filling of the receptacle and also the cleaning thereof.

Mounted in the cap and bodily carried thereby is the inclined spout tube 9, which, 50 however, may be struck from the body of the cap, or be a separate short tube with its ends inclined, as illustrated. The ends of the tube 9 as illustrated project beyond the respective faces of the cap. Also carried by the cap at a point adjacent to the center is the tube 10, which provides a vent

opening to the cap, while it also provides a passage way for the gravity actuating member, as will presently appear.

Provided through the cap are two pairs 60 of openings 11, in which are mounted the two hinging rings 12, which loosely fit in the openings 13 of the closure or flap 14, so that the closure or flap may assume the various positions as illustrated in Figs. 1 and 3. Also formed in the flap 14 is an opening 15, in which is detachably mounted the threaded end of the curved rod 16, which has mounted upon its inner end the removable weight 17, which is a cylindrical member of greater diameter than the opening of the tube 10, so that should the receptacle be turned completely upside down, the weight will not permit the flap closure to swing 70 too far away from the cap. It will thus be 75 seen that the weight will automatically move the flap into open or closed position as illustrated, and thus render it unnecessary for the operator to touch the flap closure while dispensing cream, milk, syrup, 80 sugar or the like. The nut 18 is designed to lock the rod 16 upon the closure flap 14 and also to prevent the rod from rotating, which rod is positioned to hold the weight 18 away from the spout tube 9 at all times. 85 The vent tube 10 may be struck from the cap 7, where found desirable, its outer face being in a plane with the outer face of the spout tube 9, so that when the flap closure 14 assumes the position as shown in Fig. 1, 90 both openings of the tubes 9 and 10 are sealed. By hinging the flap closure as indicated, it will always project far enough 95 away from the outlet of the spout tube 9, to not interfere with the flow of the material dispensed, thus preventing such material adhering to the same, and making it gummy and dirty.

By this construction a very neat sanitary receptacle with a gravity actuated closure 100 is provided.

What I claim, as new, is:

1. A cap for dispensing receptacles having formed therein two raised outlets, one forming a spout and the other a vent, a flap closure for both outlets hingedly connected to the cap, a rod connected to the flap closure and projecting through the vent outlet, and a weight connected to the rod at the opposite side of the cap to the flap 110 closure.

2. A cap for dispensing receptacles hav-

ing two outlet openings, one forming a spout and the other a vent, a flap closure for both outlets, a plurality of rings mounted in the cap and loosely connected to the flap closure to form hinging elements for the closure, a rod connected to the closure and projecting through the vent, and a weight mounted upon the rod and disposed upon the opposite side of the cap to the flap closure.

3. A cap for detachable connection with a container comprising a body having a flat top provided with a plurality of holes, a flap loosely connected with the flat top and adapted to normally close the holes and also to automatically gravitate to open position on inverting the cap, and a weighted rod connected to the flap and projecting

through one of the holes to form a guiding means, the weighted portion of the rod being of a size greater than the size of the hole through which said rod works to limit the swinging movement of the flap in one direction.

4. A cap for dispensing receptacles having formed therein openings, a flap closure for both openings hingedly connected to the cap, a rod carried by the closure and working through one of the openings, and a weight mounted on the rod for effecting the swinging of the closure to open or closed positions.

In testimony whereof I affix my signature.

EMORY J. BENEDICT.
